Application March 8, 1948, Serial No. 144,974

Term of patent 3½ years

(Cl. D34—15)

To all whom it may concern:

Be it known that we, Lula Jane Pyle and Maxine H. Schell, citizens of the United States, residing at Kansas City, in the county of Jackson and State of Missouri, have invented a new, original, and ornamental Design for a Table Centerpiece, of which the following is a specification, reference being had to the accompanying drawing, forming a part thereof.

Fig. 2 is an elevational view of one side thereof.

Fig. 3 is an elevational view of another side thereof; and,

Fig. 4 is an elevational view of another side thereof.

We claim:

The ornamental design for a table centerpiece, as shown.

LULA JANE PYLE.
MAXINE H. SCHELL.
